UNITED STATES PATENT OFFICE.

MATHEW BARR, OF AITKIN, MINNESOTA.

GRAB-HOOK FOR CHAINS.

SPECIFICATION forming part of Letters Patent No. 336,687, dated February 23, 1886.

Application filed November 25, 1885. Serial No. 183,995. (No model.)

To all whom it may concern:

Be it known that I, MATHEW BARR, a citizen of the United States, residing at Aitkin, in the county of Aitkin and State of Minnesota, 5 have invented certain new and useful Improvements in Grab-Hooks for Chains; and I do declare the following to be a full, clear, and exact description of the invention, such as will enable others skilled in the art to which it appertains 10 to make and use the same, reference being had to the accompanying drawings, and to the letters and figures of reference marked thereon, which form a part of this specification.

This invention relates to grab-hooks for 15 chains; and the novelty consists in the construction and adaptation of parts with a view to the service to be performed, as will be more particularly hereinafter set forth, and specifically pointed out in the claims.

20 The invention is designed as an improvement upon the device patented to M. Colgan, April 11, 1865, No. 47,241, and it seeks to overcome some of the defects of that device.

These hooks have been forged out of square 25 bars of iron so arranged that the flat sides will furnish a bearing for the links of the chain; but when thus formed the inclined sides of the two arms of the hook form a surface in which the link becomes wedged, and it frequently requires several blows from a hammer or other 30 convenient device to break the connection. A still more serious fault, however, lies in the fact that the hook thus constructed is not durable. The hook in its service is subjected to 35 great strain, and it requires a nice discrimination to give the proper strength and not have the hook bulky and unwieldy. When the hook is forged, the fiber of the metal is weakened by the act of bending it, and it is weakened at 40 the very point where the greatest strength is required—namely, at the junction of the two arms. Under the most favorable circumstances a hook thus forged is barely of sufficient strength at this junction to stand the necessary tests of 45 lumbering; but when, added to this weakening feature, the strain is brought against inclined faces, and all strain is directed to throw the arms away from each other, it results that the hook is frequently broken and is never capable 50 of withstanding the severest strains. I seek not only to overcome the difficulties men-

tioned, but to greatly broaden the capacity of the hook to receive and resist greater strains.

I cast my hook of fine steel or malleable cast-iron of the proper form and capacity. I avoid 55 the wedging-surfaces, and I am enabled to readily re-enforce the junction of the two arms of the hook by properly forming the molds at such points.

I do not rely for protection upon the fact 60 that I cast the article instead of forging it.

The novelty of the invention resides in the features of advantage which the device embodies, and these features I can more readily 65 secure by casting the hook.

The invention is fully illustrated in the accompanying drawings, which form a part of this specification, and in which—

Figure 1 is a perspective view of my improved link-hook, showing the relation of the 70 links in dotted lines. Fig. 2 is a section taken on the line *x x* of Fig. 1, and Fig. 3 a section taken on the line *y y* of Fig. 1.

I cast my hook in the shape required for service, thus leaving to the metal its full strength. 75

A designates the body of the hook, having eye *a*, and B designates the arm, the two being connected by the re-enforced junction C. This junction C is the part of the hook which is subjected to the greatest strain, and I re-enforce 80 this part, not only for the purpose of increasing the resisting capacity of the hook, but also to provide a bearing, *c*, for the link which is next to the one embraced by the arms A B.

b and *b'* designate the bearing-faces upon the 85 body A and arm B, respectively, upon either side of the link-receiving slot D. These faces, as shown, have a slight incline; but they are substantially flat, so far as any wedging effect from the link is concerned.

In Fig. 1 it will be noticed that, while the link *s* is embraced by the arms A B of the hook, the link *s'* bears fairly upon the faces *b* *b'* and rests against the re-enforce C. The arm B is not only strengthened by the re-enforce, 95 but the faces *b* *b'* prevent any wedging effect from the contact of the link *s'*. I thus not only strengthen the arm B, but I avoid any wrenching strain upon said arm.

My hook has all the inherent strength of the 100 metal and is adapted to resist great strain.

While I have specified the preferable mode

of manufacture—as by casting, it will be understood that a hook, if forged and having the flat bearing-faces b b' and having the re-enforce C as a bearing for the links, would possess some 5 of the advantages of my construction.

What I claim as new is—

1. A grab-hook for chains having approximately flat bearing-faces b b' , to receive the link of the chain without wedging strain, and 10 having a re-enforce, C , as and for the purposes set forth.

2. A grab-hook for chains, consisting of the body A , arm B , and re-enforced junction C , the said parts A B having the flat faces b b' , 15 as set forth.

3. The grab-hook described, formed of cast-steel or malleable iron, and composed of the parts A B , having flat faces b b' , and the re-enforced junction C , having link-bearings c , all arranged, constructed, and adapted to serve 20 as herein set forth.

In testimony whereof I affix my signature in presence of two witnesses.

MATHEW BARR.
